FIG. 2

FIG. 3

FIG. 4

FIG. 5

FIGURE 1 is a perspective view of a building embodying my new design and is broken away in the center to indicate an indeterminate length.

FIGURE 2 is a side elevational view thereof taken from the left of FIGURE 1.

FIGURE 3 is a side elevational view thereof taken from the opposite side of FIGURE 1.

FIGURE 4 is an end elevational view thereof taken from the left of FIGURE 3.

FIGURE 5 is an end elevational view thereof taken from the right of FIGURE 3.

The characteristic feature of my new design resides in the vertical recessed side panels in combination with the building as best shown in FIGS. 1, 2, and 3.

I claim:

The ornamental design for a building, as shown and described.
